UNITED STATES PATENT OFFICE.

HUGO HELBERGER, OF MUNICH, GERMANY.

TRANSFORMING SMELTING-FURNACE.

932,986.

Specification of Letters Patent. Patented Aug. 31, 1909.

Application filed September 11, 1908. Serial No. 452,615.

To all whom it may concern:

Be it known that I, HUGO HELBERGER, a subject of the Emperor of Germany, residing at Munich, Germany, have invented certain new and useful Improvements in Transforming Smelting-Furnaces; and I do hereby declare the following to be a full, clear, and exact description of the same, reference being had to the accompanying drawings, 10 forming a part of this specification, and to the figures and letters of reference marked thereon.

This invention relates to appliances for melting, by means of electricity, metals, 15 glass, enamel and similar materials having a high melting point, the objects of the invention being to provide a simple, thoroughly practical, compact and economical apparatus with which the materials operated on 20 may be preserved without contamination or alteration other than such changes as are incidental to the heating of the same to the desired degree.

The invention consists in certain novel details of construction and combinations and arrangements of parts, all as will be now described and pointed out particularly in the appended claims.

In the accompanying drawings: Figure 1 30 is a perspective view of an apparatus embodying the present invention, certain parts, however, being omitted for the sake of perspicuity. Fig. 2 is a diagrammatic view of the apparatus. Figs. 3, 4, 5, 6 and 7 are 35 views illustrating receptacles for the material to be melted.

Similar letters of reference indicate like parts in all the views.

It has been proposed heretofore to make 40 use of melting vessels composed of graphite and clay and the walls of which are highly heated by the passage of an electric current, and while I do not claim the same broadly as my invention it is to be noted that there 45 has been no commercial use of the idea, the apparatus heretofore proposed never having passed the experimental stage.

In the present invention a practical and economical construction and arrangement of 50 melting pot and appliances for heating the same is provided; thus as illustrated in Fig. 2 there is provided a transformer T capable of transforming an alternating or multi-phase current of high potential and low amperage into one of low voltage and great density or high amperage. The primary of

the transformer is built up of coils in series but each having one terminal f' leading to a switch or similar controller U. The high potential circuit from the coils includes a 60 generator A and an ampere meter B.

The transformer shown diagrammatically in Fig. 2 is embodied in a structure forming part of the furnace, as shown in Fig. 1. The transformer is located within the foraminous casing C held between the top and bottom heads C' and arms D projecting from the heads constitute the braces or supports for the terminal electrodes K, K', of the secondary whereby losses in the conductors may be entirely avoided. The upper electrode K' is movable whereby a melting receptacle G may be clamped between it and the lower electrode K. Conveniently the upper electrode is annular and controlled or 75 advanced by a screw and hand wheel H.

Both electrodes are preferably water cooled for which purpose they form part of a water circulating system W W' indicated in Fig. 2, but omitted from Fig. 1 to 80 avoid obscurity. In this connection it may be mentioned that in order to avoid heat losses it is advantageous to place intermediate carbon contacts of high electrical conductivity between the metal electrode and 85 melting receptacle or crucible as indicated at k k'.

The melting receptacle is the resistance element in the secondary circuit and is preferably made of graphite or a combination 90 of other materials with graphite as will be presently explained, but it is here noted that in employing such vessels particular attention must be paid to regulation, since, as is well known, graphite has a negative temperature coefficient that is to say, the resistance decreases as the temperature rises. The voltage must therefore be reduced when the crucible becomes incandescent. For this reason especially, the graphite smelting vessel is placed in combination with the transformer since the latter is capable of regulation without loss. Operation by a direct current with resistance regulation is accomplished by such loss as to be commercially 95 impracticable.

Inasmuch as incandescence first appears in that part of the vessel having the greatest electrical resistance the form or construction of the vessel becomes of importance and if 110 conductive material (metal) is to be melted it becomes of importance to confine the cur-

rent to the walls of the vessel so as to insure uniformity of operation and to prevent short circuiting. While ordinary crucibles composed of a mixture of graphite and clay 5 may be employed in the apparatus heretofore described, vessels constructed in accordance with the principles illustrated in Figs. 3 to 6 will be found more advantageous.

In Figs. 3, 4 and 7, the vessels are formed 10 with the walls intermediate the ends, of a reduced cross section as at g , the points of reduced section being selected to accord with the points where the greatest concentration of heat is desired. In Figs. 5 and 6 the 15 walls of the receptacles are composed of ingredients of varying proportions so as to increase the resistance at the desired points, for instance, the ends of the receptacles at g' may be 6 parts clay and 4 parts graphite 20 while the portions of the wall at g'' may be 6 parts clay and 2 parts graphite and the mixtures may be blended so as to secure graduated heating from the maximum at the desired point of concentration to a minimum 25 at the points of contact with the electrodes.

When metal is to be melted it should be electrically insulated from the wall of the vessel as by a non-conductive lining such, 30 for instance, as fire brick but the desired result can best be accomplished by treating the vessel while white hot with an oxygen blast whereby the graphite on the surface is eliminated leaving a layer (g^4 , Fig. 7) 35 which is an insulator of electricity.

An air blast may be employed in lieu of the oxygen blast but requires a longer time to give the desired result, so too other chemical treatment may be resorted to for removing 40 the graphite from the inner surface of the receptacle, as, for example, treatment with fusible silicates, also treatment with nitric acid and potassium chlorate etc.

Vessels constructed as above described 45 with a non-conductive inner surface may be used with equally good results for metals having a low melting point (lead, tin, zinc etc.) or for metals having a high melting point (brass, copper, silver, gold, iron, steel 50 etc.) and without such non-conductive inner surface the vessels may be advantageously used for melting or treating non-conductive materials.

Having thus described my invention, what 55 I claim as new and desire to secure by Letters Patent, is:

1. A transformer furnace embodying a transformer having terminal electrodes of its secondary windings located in proximity to and directly connected with the windings whereby current losses are reduced, said electrodes having oppositely disposed contact faces for clamping a melting crucible 60 between them and clamping means separate

from but engaging said electrodes to clamp a crucible between them. 65

2. A transformer furnace embodying a transformer having terminal electrodes of its secondary windings located in proximity to and directly connected with the windings whereby current losses are reduced, said 70 electrodes having oppositely disposed contact faces for clamping a melting crucible between them, one of said electrodes being annular to give access to the interior of the crucible, and clamping means mounted on 75 rigid supports and coöperating with the opposite sides of the electrodes to clamp a crucible between said electrodes.

3. A transformer furnace embodying a transformer having terminal electrodes of 80 its secondary windings located in proximity to and directly connected with the windings whereby current losses are reduced, a frame in which said transformer is mounted having arms projecting on the outer sides respectively of the terminal electrodes, and means carried by said arms and coöperating with the electrodes for supporting and moving the electrodes toward each other to clamp a 85 crucible between them. 90

4. A transformer furnace embodying a transformer having terminal electrodes of its secondary windings located in proximity to and directly connected with the windings whereby current losses are reduced, one of 95 said electrodes being located above the other, a frame in which the transformer is mounted having top and bottom heads, rigid arms projecting from said heads above and below the electrodes respectively, one of said 100 arms forming a support against which one electrode rests and a clamping device on the other arm and coöperating with the other electrode to clamp a crucible between the electrodes. 105

5. A transformer furnace embodying a transformer having terminal electrodes of its secondary windings oppositely disposed to clamp a crucible between them, both of 110 said electrodes being provided with internal ducts for the circulation of a cooling medium.

6. A transformer furnace embodying an induction transformer, terminal electrodes for the secondary windings and a melting vessel held between said electrodes to form a part of the secondary circuit, said vessel having integral walls of low conductivity with its interior face rendered electrically non-conductive by the elimination of the 120 conductive material therefrom while the body and outer part remains conductive.

7. A transformer furnace embodying an inductive transformer, terminal electrodes for the secondary windings and a melting vessel held between said electrodes to form 125 a part of the secondary circuit, said vessel

having integral walls with graphite embodied therein to form a conductive element and having its inner face rendered electrically non-conductive by the elimination of 5 the graphite while its body and outer part remains conductive.

8. A transformer furnace embodying an inductive transformer, terminal electrodes for the secondary windings and a melting 10 vessel held between said electrodes to form a part of the secondary circuit, said vessel

having integral walls with graphite embodied therein to form a conductive element and having the inner face rendered electrically non-conductive by blowing oxygen into 15 the vessel when heated by the passage of current therethrough.
